UNITED STATES PATENT OFFICE.

WILHELM ARNEMANN, OF HAMBURG, GERMANY.

PITCHING-MACHINE.

SPECIFICATION forming part of Letters Patent No. 440,296, dated November 11, 1890.

Application filed August 19, 1890. Serial No. 362,411. (No model.)

To all whom it may concern:

Be it known that I, WILHELM ARNEMANN, engineer, of the city of Hamburg, in the Empire of Germany, have invented a new and Improved Pitching-Machine for Pitching Barrels, of which the following is a specification, reference being had to the accompanying drawing.

Machine-pitching has hitherto been performed by forcing atmospheric air by means of a blower through a coke fire, and then causing said air in a heated state to pass through pipes into the barrels to be pitched. This is done for the purpose either of melting the old pitch off from the interiors of the barrels or to heat the latter for the reception of new pitch. The gases produced by these machines are in consequence of incomplete combustion often mixed up with carbonic oxide, which gas is poisonous and disagreeable to the workmen manipulating the barrels, and if mixed with the molten pitch it spoils the taste of the beer afterward filled into the barrels. Furthermore, the carbonic-oxide gases often produce explosions within the barrel in cases when mixed up therein with certain proportions of fresh air. Another disadvantage of the old machines is that small particles of coke are injected with the heating gases into the barrels or thrown into the nozzles of the blowing-pipes, thereby being caused to adhere with the molten pitch to the barrel or to plug the openings of the air-nozzles.

The object of the present invention is to obviate all these disadvantages. This is attained by dividing the combustion-chamber of the machine into two compartments, one above the other, with a communicating gorge or contracted throat between them. The hot air passes from the lower compartment, which contains the fuel, through the gorge into the upper compartment, and from the latter into the pipes leading to the barrels. Before passing through the gorge the hot air and gases ascending from and within the lower compartment are mixed with fresh air forced in jets from outside. These jets of fresh air are directed from above against the gorge or into the lower compartment and have the effect of throwing back all solid particles of coke that

may be mixed with the hot air and gases coming from the said lower compartment, and they further insure a complete combustion of the poisonous oxide gases mixed up with the heating-gases.

55

The invention is illustrated in the accompanying sheet of drawing, which represents a central vertical sectional view of my improved machine.

A is the lower compartment of the combustion-chamber. This compartment is partly filled with coke into which fresh air is introduced from below through grate R. This air comes from a blower and is forced through pipe m into a space underneath the grate.

65

A' is the upper compartment divided by a gorge or contracted throat E from the compartment A. From this compartment A' the compressed air is led into the barrels B by means of tubes o. By means of tubes x x jets of fresh air are forced into the top of the compartment A in a direction against the heated air and gases coming from said compartment A. These jets of air may be taken from the air coming from the blower before it passes through the grate R, or it may be taken from any other suitable reservoir containing compressed air or fed by another separate blower.

75

P is an opening in the top of the machine for feeding coke into the combustion chamber or compartment A.

80

What I claim as my invention is—

The combination, in a machine for pitching barrels, of a combustion-chamber in two compartments A A', arranged one above the other and communicating through a gorge E, fresh-air tubes x, for delivering air in jets against the heated air and gases arising from the lower compartment, and pipes o, leading from the upper compartment for conducting to the barrels the air and gases which have been received in the said upper compartment from the lower compartment and air-tubes and mixed in said upper compartment, substantially as and for the purpose set forth.

WILHELM ARNEMANN.
